TIMER AND SIGNAL CIRCUIT

Alvin O. Olafson, St. Paul, Minn., assignor to
 National Traffic Signal Company, St. Paul,
 Minn., a corporation of Minnesota

Application August 25, 1930, Serial No. 477,510
 Renewed April 29, 1937

12 Claims. (Cl. 200—27)

My invention relates to a timer and circuits for traffic signals wherein a variable timer which operates automatically is provided. The timer is operable to control the circuits for traffic signals, 5 having means for accomplishing certain results in a simplified manner and to provide such circuits as will permit the signals to be readily controlled, from either the fire department or police headquarters, or at the intersections of highways. 10 A feature of the invention resides in providing a timer which may be readily set to vary the time of signalling and to control the traffic signal circuits. The timer includes mechanical operating parts which provide a constant regulating means 15 for the circuits of the traffic signals, which can be easily set by the traffic department or police officers. The timer may act as a variable timing means for the signal circuits, or it may be employed as a master timer with a slightly slower operating speed than the individual timers, which the master timer is to control. The timer may further be employed as a receiving timer to be controlled by the master timer, or it may be co-ordinated with other timers in a manner to act as a progressive signal receiving and timing means. 20 A feature of my timer resides in a means of permitting the operation of the timer by a key which is adapted to enter into the casing supporting the timer and operate the necessary 25 means to control the timer, and thereby regulate the signalling circuits. This permits a traffic officer to operate the timer and signals manually, without making it necessary to open the timer casing or interfere with any of the parts. A feature 30 of the timer resides in means for automatically readjusting itself to the normal set operating functions, so that even if a timer is operated by a traffic officer by manual control, and it is left out of time with its normal operation, it will automatically readjust itself to operate to co-ordinate 35 with other timers or the master timer and circuits of the signalling system. 40

The invention includes the method of providing traffic signalling circuits for operating traffic signals controlled by the timer means, either individually by a timer for each signal or a group of signals at an intersection, or by a series of signals extending in progression along a highway or street and a master timer for controlling the 45 individual timers.

The method further includes a traffic signalling system having circuits which are adapted to operate a traffic signal wherein each signal is provided with a distributor which operates and 50 controls the signal lights of the signal, and indi-

cating means if desired for indicating the change of traffic and the means for operating the distributor. In this system, the distributor controls the making and breaking of the circuit for the signal light. This reduces the electric current which must pass through the timer for operating the signal, that is the timer make and break points for operating the signal. The only current that is necessary to go through the timer switch make and break points for controlling the signals, 5 is the current necessary to operate the small electric motors in each of the signals. Thus, I reduce the possibility of having trouble with the breaker points in the timer to a minimum. This 10 is an important feature in traffic signal systems and methods of signalling traffic.

It is also a feature of my timer and traffic signalling circuits to provide a means so that the current is off of the timer signal control switch at the time that it makes a break in contact, and thus there is no arcing of the point at the time that the circuit is broken. This insures long wear and virtually perfect continuous operation of my timer and circuits for signalling traffic. This 15 feature is accomplished in the circuits of the traffic signals in the individual distributors which control the signal lights and the means for operating the individual distributors.

A further feature of my circuits for traffic signals resides in means permitting the traffic signals 20 to be switched to a red signal all around so that traffic may be stopped, from the fire department, police headquarters, or any other convenient points, or by the officer at the particular intersection, the circuits being so arranged and controlled by the timer with the distributors to cause 25 them to automatically readjust themselves back to normal operation at any time that they have been operated out of their normal setting. This 30 provides a very desirable control for traffic signalling means.

In my timer and traffic signal circuits, the arrangement is such that the timer cannot stay out of time even though any timer may be held out of time with any other timers, or with its normal 35 setting by manual operation by a traffic officer, or in making adjustments or repairs, and owing to the arrangement of the parts, the timer will automatically readjust itself to normal operation and 40 will continue to operate in this manner until it 45 has been reset to a different operating schedule. The adjustment and setting of my timer to operate the signal circuits is of extreme simplicity and may be accomplished very quickly, even by 50 one not skilled in the setting and operation of 55

traffic signal timers or circuits. This makes my traffic signalling system and timer virtually fool-proof and reliable.

The timer and controlling circuits for the traffic signals, together with the full details will be more fully and clearly set forth throughout the specification and claims.

In the drawings forming a part of this specification:

10 Figure 1 illustrates a side view partly in section, and part broken away, of the casing for supporting the timer of my traffic signal.

Figure 2 is a front view of the open timer casing, the standard being broken away.

15 Figure 3 illustrates a detail showing the manner in which a key may be inserted from the outside of the casing to operate the timer.

Figure 4 illustrates another detail showing the operation of the timer by a key from the outside 20 of the casing.

Figure 5 illustrates a front view of the timer removed from the casing.

Figure 6 is a sectional detail through the timing disc, taken through the pointer plate and 25 switch operating lug.

Figure 7 is an end view of the timer.

Figure 8 is a rear view of the timer.

Figure 9 is a detail of a portion of the timer.

Figures 10, 11, 12, 13, 14 and 15 are diagrammatic details of the rotary operating cams and 30 booster of the rotary switch of the timer.

Figure 16 is a plan view of the timer.

Figure 17 is a detail of the same.

Figure 18 is a diagrammatic illustration of the 35 wiring circuit for my traffic signals.

Figure 19 illustrates diagrammatically my signalling circuit with a master timer controlling the individual timers for each signal.

In the drawings of this application, the timer 40 A is adapted to be supported within the casing B which is mounted upon the standard C. The casing B is formed with a drop front 10 which is adapted to drop down as illustrated in Figure 1 so that the timer may be accessible. The timer is mounted upon a sliding base which is carried 45 in the casing B and which may be drawn out above the drop front 10 so that the entire timer is easily accessible whenever it is desired.

The mechanism of the timer is mounted upon 50 the base portion 11 and on one side a transmission 12 is provided with a series of reduction gears which are operated by the electric motor 13 mounted on the base 11 in the back of the same. An operating shaft 14 extends out of the transmission 12 and the outer end of which is supported in a suitable bearing 15 carried by the upright bracket 16 which projects upwardly from the base and which is supported thereby. The bracket 16 also supports a shaft 17, the shaft 17 55 extending virtually at right angles to the shaft 14 and is adapted to carry the timing disc 18.

The bracket 16 is formed with an upwardly 60 projecting portion 19 which extends above the shaft 17 at the inner portion of the bracket and this upwardly projecting portion forms a support for the front plate 20 to position the same adjacent the timing disc 18. The plate 20 is also supported by the bracket lug 21 shown in Figure 16 of the drawings projecting upwardly 65 from the casing of the transmission 12.

The timing disc 18 is provided with a series or 70 rows of concentrically disposed pins 22 projecting from the back of the timing disc 18 and these pins are engaged by the gear 23 which is set in 75 the desired position on the shaft 14 to engage

the row of pins 22 to drive the timing disc 18 at the desired speed of rotation to operate the disc 18.

The gear 23 is operated by the engagement of the member 24 which engages between the sides 5 25 of the collar formed on the side of the gear. The member 24 is connected to the slideable plate 26 which is slideably supported on the shaft 27 by the ears 28 which project from the back of the plate. The plate 26 is supported in back 10 of the plate 20 and projects upward to the upper edge of the plate 20 with an engaging lug 29 formed on the upper edge of the plate 26 so that the plate 26 may be engaged from the front of the timer A to move it back and forth on the 15 shaft 27. The movement of the plate 26 is for the purpose of changing the position of the gear 23 so that the gear 23 may be placed into engagement with any of the rows of concentrically disposed pins 22 which operate the timer disc 18. I 20 provide a suitable catch 30 for holding the plate 26 in operative position which is pivoted to the plate 26 at 31 and by operating the free end 32 to lift the pointed end 33 which projects over the top edge of the plate 20 and engages in the 25 notches 34 of the plate 35, the plate 26 may be released so as to slide it back and forth on the shaft 27 to change the position of engagement of the gear 23.

The plate 35 is divided into a series of squares 30 36 with indicia to indicate the ratio of rotation of the timer disc 18 by the change of the gear 23 with the pins 22. In the spaces 36 I have provided the relative ratio of time for the operation of the timer disc 18. In the position in which the 35 end 33 is set in Figure 5, the operating ratio is such that it will take thirty seconds for the full rotation of the timer disc 18. When the pointed end 33 of the catch 30 is set in the notch 34 at the extreme left end of the plate 35, it will take 40 just ninety seconds for the timer disc 18 to make a single rotation.

The timer disc 18 operates the timer control switch D which is mounted on the base 11 and which is adapted to control the circuits of my 45 signalling system as will be hereinafter more fully set forth. The disc 18 is provided with a fixed control switch operating lug 37 positioned at a point as illustrated in Figure 5. An adjustable control switch operating lug 38 is normally positioned circumferentially adjustable on the disc 18 to form equal or unequal angles with respect to the lug 37 as illustrated in Figure 5. The operating lug 38 is formed with a slideable plate 39 having an operating handle 40 together with 50 a setting lug 41 which engages in the notches 42 formed on the periphery of the operating disc 18. The plate 39 extends across the axis of the disc 18 and is formed with a pointed indicating end 43 which points to the arcuated gauge plate 44 on 55 the face of the disc 18. A suitable pin 45 extends through the slot 46 in the plate 39 and by means of a coil spring 47 which engages with the pin 45 and a pin 48 fixed to the plate 39, the lug 41 is held normally in one of the notches 42 to hold the operating lug 38 in its set adjusted position.

By engaging the handle 40 the lug 38 may be 60 adjusted either toward one side or the other of the center of the gauge plate 44. One side of the gauge plate 44 may represent the East-West direction for the red which I have designated by the indicia "E. W.", with a red mark below the same, and the other side can represent the East-West for the green which I have indicated by the 65 70 75

indicia "E. W." with a green mark below on the face of the disc 18. This provides a ready direction for the operator so as to simplify the setting of the timer A.

5 The control switch D of my timer A is pro-
vided with the terminals 50 and 51 which are
supported upon the base 11 and between which
the switch arms 52 operate. The arm 52 is
mounted on the terminal 53 as indicated in Fig-
10 ure 16. The arm 52 is adapted to support the
contact point arms 54 and 55 which carry the
contact points for contacting with the terminals
50 and 51.

Below the arm 52 I provide an operating plate 15 56 for the arm 52 which is pivoted to the base 11 at 57. The plate 56 carries shoulders 58 and 59 formed of fibre or other suitable insulating material and which are adapted to engage with the arms 54 and 55 in the operation of the plate 20 56. The rear end of the plate 56 carries a pair of upwardly extending operating ends 60 the purpose of which will be hereinafter described.

The plate 56 is adapted to be held in operative position by the spring key plate 61 which is pivoted at 62 and which is formed with an upstanding lug 63 through which the rod 64 slideably operates. The rod 64 is provided with a collar bearing member 65 which engages with the lug 63 through which the rod 64 extends and an adjustable shoulder 66 is threaded on to the rod to adjustably support a coil spring 67 on the rod 64 between the shoulder 66 and the collar 65. The inner end 68 of the rod 64 is bifurcated to engage the upstanding operating lug 69 of the plate 56 as illustrated in Figures 5 and 17.

50 plate 56 as illustrated in Figures 5 and 11. The operating lug 69 is formed with a recess 70 in the edge into which the bifurcated end 68 is adapted to engage so that the spring key plate 61 with the rod 64 will operate to hold the plate 40 56 in a set position with the rod 64 bearing in the notch 70 of the plate 56 as illustrated in Figure 17 to hold the plate 56 with the spring key 61 pressing on one side of the center or pivot point 57 of the plate 56. In this position the insulating lug 59 engages against the arm 55 to hold the arm 54 by spring tension against the breaker points of the terminal and the arm 54, thus closing the circuit through the terminal 45 50 and through the arm 52 through the terminal 53 when in this position.

50 55 60 65 70 75 The key plate 61 carries two operating pins 71 and 72 in the form of rotatable sleeves carried on suitable pins projecting up from the plate 61. The pins 71 and 72 are adapted to be engaged by the operating lugs 38 and 37, respectively, the lug 37 engaging with the pin 71, while the lug 38 will engage with the operating lug pin 72. Thus in the rotation of the operating timer disc 18 the lugs 37 and 38 will engage with the operating pins 71 and 72 of the spring key 61 to throw the plate 56 from one side to the other to make and break the contacts by the arms 54 and 55 with the terminals 50 and 51. When the operating key 61 is in the position illustrated in Figure 17 the rotation of the timing disc 18 will cause the lug 38 to engage the pin 72 to rotate the spring key plate 61 to cause the rod 64 to push the lug 69 into the position indicated in dotted outline, shifting the plate 56 into the position illustrated in dotted outline and holding it in this set position under spring tension of the key plate 61 until the lug 38 rotates to engage the pin 71 and shift the plate back into the full line position illustrated in Figure 17. In these operations the contacts of the terminals 50 and 51 are made

and broken to control the circuits of my traffic signalling system. The lugs 37 and 38 have beveled engaging faces to provide the cam-like operating surfaces for engagement with the pins 71 and 72.

The signal control switch D operates to snap to close the circuit through either the terminal 50 or 51. The operation is quick without hesitation and positive to close either one circuit or the other such as will be hereinafter described. 10

The timer A is provided with an auxiliary circuit controlling switch E having a rotary cam-operating means, the functions of which are similar to those of the control switch D. The auxiliary switch E is provided with a top spring switch arm 73 having two breaker points 74 positioned adjacent each other on the under side of the same. These terminals are adapted to engage with the terminals of the switch arms 75 and 76, respectively, which are positioned directly below the switch arm 73 and which extend and are attached to the under side of the insulating supporting member 11. The arm 73 is attached to the top of the insulating supporting member 11, thus providing a three-way circuit control switch E with one of the switch members, such as 73, being common and having the two breaker points 74. Either of the breaker points 74, that is, either one or the other, are adapted to contact with the breaker points of the arms 75 and 76 so that normally either one or the other of the arms 75 or 76 are in operative position to contact with the breaker points 74.

The switch arm 73 has a circuit terminal 78 on the insulating member 71, while the arm 75 has a terminal 79, and the arm 76 a terminal 80. These terminals are positioned adjacent each other on the insulating support 71. 35

The switch arm 73 has a spring nature so as 40 to extend down toward the arms 75 and 76 and I provide an insulating stop lug 81 which projects between the free ends of the arms 75 and 76 to limit the downward movement of the arm 73. The stop lug 81 is carried by a suitable supporting bracket from the bracket arm 16. 45

The arms 75 and 76 are adapted to be operated by the rotatable cams 82 and 83, respectively, which are carried upon the shaft 17. The cams 82 and 83 are connected integrally and supported by the collar 84 which also supports the booster cam 85 which is positioned adjacent the cam 83. The booster cam 85 is engaged by the pin 86 which is carried by the collar 87 and the collar 87 is fixed to the shaft 17 by the screw 88 so that when the shaft 17 is rotated by the operating timer disc 18 the cams 82, 83, and 85 will be rotated therewith. A suitable slot 89 is formed in the booster cam 85 so that a certain amount of play is permitted between the collar 87 and the cams to permit the booster cam to be operated by the spring booster arm 90 to advance the position of the cams 82 and 83 in a certain point of rotation of the cams in the operation of the timer A. The spring arm 90 is provided with an anti-friction cam engaging wheel 91 which operates against the booster

In the operation of the timer A the auxiliary switch E is operated by the rotation of the cams 82 and 83 carried around by the collar 87. A dia-grammatic illustration of the operation of the cams is illustrated in Figures 10 to 15, inclusive. Figures 10 and 11 illustrate the cam 82 showing the position of the cam just prior to the break- 70

ing circuit by the arm 75 in Figure 10 and in Figure 11 showing the circuit broken. Figure 12 illustrates the circuit controlled by the arm 76 open, while Figure 13 shows the circuit controlled 5 by the arm 76 closed. Figure 14 illustrates the position of the booster cam 85 just prior to its boosting operation and Figure 15 shows the same 10 after the boosting operation. Figures 10, 12 and 14 show the relative position of the cams 10 82, 83 and 85 at a single point of rotation, while Figures 11, 13 and 15 show the same cams in the next succeeding position. Thus as the circuit in the auxiliary switch E is broken as to the switch arm 75, like in Figure 11, the booster 15 cam 85 will operate automatically to close the circuit controlled by the arm 76. In this manner the auxiliary switch E operates similarly to the control switch D and the switch E may be used as a control switch for circuits of my signalling 20 system as will be hereinafter pointed out. In the control switch D or control auxiliary switch E, breaking of one circuit is followed by the immediate closing of another circuit automatically in the operation of the timer A. With this in 25 mind the operation of my signalling circuits will be more readily understood to indicate the advantages of my traffic signalling circuits and timer.

The master timer F may be identical to the 30 timer A just described, excepting that it is not necessary to employ a signal control switch D. Ordinarily a circuit controlling switch E is best adapted for the master timer F, because the master timer F is only necessary to control the timers 35 A of the individual signals G to keep the individual timers synchronized. The division of time such as is capable by the operating disc 18 is not necessary in the master timer, therefore it is not necessary to use the signal control switch 40 D. Figure 19 illustrates diagrammatically the master control timer F in control of the several timers A and in this diagram of my signalling circuit I have shown the individual signals as represented by G. The diagrammatic showing 45 of the signals G shows only the motor circuit which operates the distributor H which is shown diagrammatically in other circuits which will be later referred to. The timers A which are controlled by the master timer F and which operate 50 the individual signals G have both the switch D and E. The switch E operating to synchronize with the switch E of the master timer, controls the operation of the individual motors 13 of the timers A.

55 The individual timers A operate a little faster than the master timer F. This permits the individual timers to be kept in time by the master timer, causing them to be started at the same time and thus kept in synchronism after they 60 have been set.

Figure 19 illustrates the manner in which a master timer controls individual timers A. At the top of Figure 19 is illustrated the master timer F and beneath this timer are illustrated 65 three timers A. It will be noted that in the timers A, the circuit to the motors 13 extends through the switches E. Each contact of the switch E is connected through the corresponding contact in the switch E in the master timer 70 F. Accordingly corresponding contacts in the switches E, both in the master timer and in the timers A must be closed before the motors 13 in the timers A will run.

75 As has been stated, the timers A run a little faster than the master timer F. Therefore, the

motors 13 of the timers A will shift the switches E and cause these switches E to break the circuit to the motors 13 thereof before the switch E of the master timer F is operated. Thus, for a short period of time, the motors 13 of the timers A cease operation. When the switch E of the master timer F is shifted by its cam means, corresponding contacts in the switches E of the timers A and of the timer F are again closed, closing the circuit to the motors 13 of the timers A, and causing them to operate until the switches E are again shifted by their cam means.

To set the timers A in operative relation to the master timer F the set screw 88 of the collar 87 is released and all of the timers A are set with the wheel 91 in the same position on the booster cam 85, preferably with the wheel 91 in the recess of the cam as illustrated in the diagram in Figure 15. The collars 87 are then 20 made secure to the operating shaft 17 and the master timer F will then control the individual timers A to keep them all synchronized and timed by the master timer.

The individual timers A control the motors 92 25 of the signals G. The timers A operate to control the motors 92 through the switches D of each of the timers. In the diagrammatic illustration of the wiring in Figure 19, that portion 30 of the distributor H which carries the two switches for operating the motor 92 is illustrated. This portion of the distributor H which carries these two switches is 93.

In Figure 18 I have illustrated the wiring diagrams for the signals G and in this diagram I 35 have illustrated the light circuits of the signals, such as 94, 95, and 96, which represent the red lights of the signal by 94, the amber or change lights by 95, and the green lights of the signal by 96. In this diagram the circuit switches of 40 the distributor H are all shown. The amber switches of the distributor H are illustrated at 97, while the red and green switches of the distributor are indicated at 98. The switches of the distributor H such as 93, 97, and 98, are 45 operated by the rotation of the motor 92 in each signal G and when the motor 92 is at rest the distributor cams, not illustrated in the drawings, which operate the switches in the divisions 93, 97 and 98 of the distributor H are inoperative. When the motor 92 starts to operate the 50 switch cams in these respective parts 93, 97, and 98, will begin to operate so as to operate the respective switches therein and close or open the respective circuits as will be readily understood from the circuit wirings.

In my signal if at any time a traffic officer desires to operate the individual signals G at any corner or intersection, manually, it is only necessary for the officer to step up to the timer 60 control box B and insert the key 99 into the key receiving cylinder 100 which permits the officer to operate the rod 101 and this rod 101 will operate the operating ends 60 which project from the plate 56 so as to manually operate the 65 arms 54 and 55 which control the circuits of the switch D to operate the signal at the intersection manually by the officer. Should the officer desire to throw a red signal light all around at the intersection to stop the traffic, it is only 70 necessary for the officer to place the key 99 in the key receiving cylinder 102 in the upper part of the casing B which will permit the rod 103 to be operated and the operation of this rod will 75 operate the gang switch 104 closing the necessary

circuits, so as to turn the red lights 94 on all around the signal G. In this manner any traffic officer can operate the individual signals G manually when it is desired. As soon as the 5 officer releases the key from the casing or timer box B, the signal G will automatically be readjusted and timed with any signals G that it is in time with controlled by a master timer F. If the signals A are used individually without 10 the master timer F the signal A will automatically readjust the timing of the signal lights 94, 95 and 96.

I have provided in my circuit as illustrated in the diagrammatic illustrations in Figure 18, a 15 switch 105 which when the switch is in the position illustrated leaves the circuits of the signals G in ordinary running or normal operative position. If the switch blades 106 are turned into contact with the contacts 107 of the switch 105, 20 the signal lights G will show the red lights all around and will remain this way until the switch 105 is thrown back to normal operating position. This switch 105 may be placed in the fire station or at any convenient place for the operation 25 of the signals G.

A second control switch 108 is illustrated in Figure 18 in which the normal running position of the signals G is illustrated. This switch 108 may be placed in the police department or 30 any other convenient position and when the switch blades 109 of this switch are thrown to the terminals 110, the red lights 94 will be lit all around the signals G. Thus it is apparent that the switches 105 and 108 as well as the individual switches 104 in the timer box B, permit the manual operation of the signals G to indicate red all around to stop the traffic if it is desired. These switches show clearly the ready control from various points of my signals G.

40 My signals G are each provided with an indicator I which is operated by the motor 92 of each of the signals which operates the distributor H. This indicator is illustrated diagrammatically, being in the form of suitable indicating fingers 45 116 over the amber lights 95 to indicate the time of change of the signal lights from red to green and from green to red, so that the traffic may be warned of the time of change and so that a positive signal to indicate the remaining time 50 before the change takes place will be before the eyes of the traffic. In the diagram in Figure 13 I have illustrated the wiring in a manner so that if the switch 105 is operated to turn the red lights on all around, the motors 92 will continue to run until the indicating fingers I have come to an invisible position in the casing, at 55 which time they will automatically shut off.

My timer and circuits operate to control the traffic signals G in a manner so as to permit the 60 signals G to be set at progression so that one signal after the other will operate to permit travel of traffic in certain directions. The master timer F will control the individual timers A and the circuit which shows this in its simplified form 65 is illustrated in Figure 19. This circuit does not show the signal lights of the signals G but shows the operating motors 92 for the distributors H. The signal lights such as 94, 95, and 96, are 70 illustrated in Figure 18. Each series of lights 94, 95 and 96 are composed of four lights, one for each side of the signal. More or less of these lights depending on the number of sides for indicating for the signals G may be provided. The circuits are of a simple nature and indicate the 75 manner in which my timer A may operate to

control the same. It will be noted that the load of the lights is not carried through the breaker points carried by the arms 54 and 55, but rather the load of the lights of the various signals pass from the individual distributors H direct to the 5 line supplying the current. This structure is distinctly different than other signals and permits the breaker points of the arms 54 and 55 to be operated with the minimum load being that of the operation of the motors 92 only. The breaker 10 points for the master timer have the same advantage as the breaker points in the individual timers A, in that they only carry a sufficient load for the operation of the motors 13. In this simplified structure I have provided a timer A which 15 is dependable as is also the signal G with its distributor H. The distributors H handle the light circuits in each signal and each timer operates to regulate its individual signal or a series 20 of signals from any of the timers A, while the 20 timers A are controlled by the master timers F. The manner in which the master timer F controls the timers A has already been described.

By my timers and traffic signal circuits the 25 signals may be easily controlled either from police headquarters, the fire department, or at any other convenient places and provide controls for the traffic officer at the individual timers. The keys 99 are constructed with the receiving cylinders 100 and 102 so that the officer cannot 30 remove the key until he turns the same back to normal position and even though the particular signal G which was controlled by the timer which the officer operated was left with the signal out of time with other signals such as G which were 35 being controlled by a master timer F, this timer would automatically readjust itself to operate in proper time with the other signals. This is accomplished by the motors 13 of the individual 40 timers A running faster than the master timer motor and thus permitting the master timer to cause all of the motors 13 to start at the proper time. The timers A with their operating disc 13 permit the individual signals G to be operated at 45 any desired time to change the signal lights and to permit the time allowed for traffic to pass to be divided as hereinbefore described by setting of the operating lug 38 with the pointed end 43 of the slideable plate 39 pointing in the direction of the division desired. The timers A provide 50 a flexibility of adjustment of a very desirable nature, are simple to set by means of the adjustable plate 39 which carries the lug 38 and the operating key 33 in the notches 34 so as to change the ratio of operation of the operating disc 13. 55 These features together with the advantages of carrying a small amount of current in the breaker points of the operating parts are of primary importance in the operation of my timer and circuits for traffic signals.

In accordance with the patent statutes I have described the principles of operation of my timer and circuits for traffic signals and I have endeavored to represent the best embodiment thereof; the changes which are obvious and apparent with the foregoing description are a part of this invention within the scope of the following claims.

I claim:

1. An electrically operated timer for traffic signals and the like comprising, a timer operating shaft, and a rotatable cam circuit closing switch having booster cam means therein adapted to cause an electric circuit to be closed when a circuit is opened by said switch.

2. A timer for traffic signals comprising, an electric motor, a transmission operated by said motor, a timer disc operated by said transmission, a circuit make and break switch operated by 5 said timer disc, operating lugs for said circuit make and break switch carried by said timer disc, means for adjusting said lugs in relation to each other, an auxiliary circuit switch having cam means operable from said timer disc shaft, 10 and a booster in said auxiliary switch adapted to cause the closing of a circuit automatically with the breaking of another circuit.

3. A timer for operating traffic signal circuits including, an electric motor, a timer disc operated by 15 said motor, a snap make and break circuit switch operated by said timer disc adapted to close a circuit automatically when another is opened, an auxiliary cam operated switch having means for automatically closing a circuit when 20 one is opened, and means for manually controlling said snap make and break circuit switch independent of said timer disc and motor.

4. A timer for controlling traffic signals including, an electric motor, a timing member operated by 25 said motor, two circuit switches operated by said timer member, one having spring flexible contact means to flex into position to close a circuit while simultaneously opening a circuit, and the other having rotatable cam operating and booster means to open a circuit and simultaneously close another circuit.

5. In combination, an electric motor for operating a timer, a timer disc operated by said electric motor, a rotatable circuit breaker switch operated by 35 said timer having a booster cam means adapted to cause said circuit breaker switch to close a circuit when one is broken, a three-way switch for operating traffic signal circuits, and means carried by said timer disc adapted to operate said three-way switch to close one circuit when the other is broken, and a snap plate and key which control said switch operable by a means carried by said timer disc for operating said three-way switch.

45 6. A timer for traffic signal circuits including, an electric motor, a timer disc operated by said motor, switch operating lugs adjustably carried by said timer disc, a three-way switch adapted to be operated by said lugs, a rotatable plate 50 having insulating ends for engaging with said three-way switch to hold the same in operative position to normally close an electric circuit while another circuit is broken, and a spring key operated by said switch operating lugs carried by 55 said timer disc.

7. A timer for circuits for traffic signals including, an electric motor for operating the same, a rotatable timer member operated by said motor, a switch including a bifurcated switch arm having two contact terminals, a switch operating plate adapted to hold said switch arms to normally close one of said terminals to close a cir-

cuit, a spring operated key for operating said switch operating plate, and lug means carried by said timer member to operate said key to move said switch operating plate and to automatically throw said bifurcated switch arms from one terminal to another, thereby making a circuit when one is broken. 5

8. A timer for electric circuits including, an electric motor, a rotatable switch, a timer member adapted to be rotated by said motor, booster means in said rotatable switch to cause said switch to close a circuit when another circuit is broken, a separate snap circuit opening and closing switch operated by said timer member, a spring key for operating said snap circuit opening and closing switch, a switch arm holding plate operated by said key, and adjustable key operating means for said snap switch operating key carried by said timing member, said rotatable switch being adapted to operate two circuits while 10 said snap switch is adapted to operate two other circuits in the operation of said timer. 15

9. A timer for signal circuits including, an electric motor, a timer member operated by said motor, a rotatable make and break switch having means for opening one circuit and simultaneously closing another, and a snap switch having means for closing a circuit while simultaneously opening another, each switch being operated by 20 said timer member in the rotation thereof. 25

10. In a timer, a contact, a pair of terminals between which said contact may move, a pivoted shifting plate for engagement with said contact to force said contact selectively into engagement with one or the other of said terminals, a movable key plate, means interposed between said key plate and said shifting plate for holding the plates in one extreme position or the other, cam engaging pins on said key plate, and cam means for shifting said key plate from one extreme position to the other. 30 35

11. In a timer, a timer disc, means for rotating the same, a shaft thereupon, a flange secured on said shaft, a collar rotatable on said shaft, a booster cam on said collar, a pair of contact closing cams secured on said collar, means in spring engagement with said booster cam, and a pin and slot connection between said collar and said flange for rotating said collar with said shaft whereby said spring means causes a sudden advancement of said collar and contact closing cams during the rotation of said shaft. 40 45 50

12. In a timer, a cam shaft, a collar thereupon, clutch means interposed between said collar and said shaft to drive said collar from said shaft, a booster cam and contact closing cams secured on said collar, and resilient means in engagement with said booster cam acting thereagainst to suddenly advance said collar on said shaft in the direction of rotation thereof. 55 60

ALVIN O. OLAFSON.
